UNITED STATES PATENT OFFICE.

ALPHONSUS L. GOLDEN, OF OAKLAND, CALIFORNIA.

STARTER FOR INTERNAL-COMBUSTION MOTORS.

1,157,690.

Specification of Letters Patent.

Patented Oct. 26, 1915.

Application filed December 17, 1914. Serial No. 878,816.

To all whom it may concern:

Be it known that I, ALPHONSUS L. GOLDEN, a citizen of the United States, residing in the city of Oakland, county of Alameda, and State of California, have invented a new and useful Improvement in Starters for Internal-Combustion Motors, of which the following is a specification.

My invention relates to starters for internal combustion motors wherein each cylinder of the motor is provided with a chamber containing a quantity of properly mixed explosive gas, said chamber operating in conjunction with suitable means for releasing the compressed gas into the motor cylinders; and the objects of my invention are first, to provide an auxiliary charge of compressed explosive gas adjacent to each cylinder of the motor; second, to provide means whereby the igniting system may be temporarily disconnected and a charge of gas from the cylinder compressed into the chamber therefor; third, to provide improved means for releasing the compressed charge of gas from the chamber into the cylinder; and fourth, to provide means for properly obstructing the connection between the cylinder and the chamber and igniting the charge within the cylinder. I accomplish these several features by means of the device disclosed in the drawings forming a part of the present specification, wherein like characters of reference are used to designate similar parts throughout the said specification and drawings and in which—

Figure 1 is a broken side elevation of the front end of an automobile, disclosing my invention applied thereto. Fig. 2 is a vertical sectional view taken through one of the cylinders, the compressed gas cylinder and the valve connecting the said cylinder with the said chamber, the valve being shown in a charging position. Fig. 3 is a vertical sectional view of the valve disclosing the same in a position for closing the connection between the chamber and the cylinder. Fig. 4 is a view similar to Fig. 3 but with the valve disclosed in a position that will release the compressed gas from the chamber into the cylinder. Fig. 5 is a vertical sectional view of the valve only taken on line X—X of Fig. 2, and Fig. 6 is a front elevation of the indicator and means for operating the valve affixed to the dashboard of the vehicle.

Referring to the drawings, the numeral 1

is used to designate a series of compressed gas chambers connected to the cylinders 2 of an internal combustion motor, by means of the valve casings 3, said casings 3 being each provided with the upper and lower channels 4 and 5, respectively, which furnish a means of communication between the chambers 1 and the interiors of the cylinders 2. A valve 6 is rotatably mounted 60 within each valve casing 3, said valves 6 each being provided with the channels 7 and 8, respectively, arranged transversely to each other. The channel 8 is provided with a suitable valve 9 arranged to normally prevent the flow of gas through the said channel in one direction only. Each valve 6 is provided with an annular flange 12 and an extension rod 14, said extension rods 14 being also provided with flanges 15 and 65 threaded extensions 17 adapted to engage the valve adjacent thereto. The valve 6 nearest the dash board 26 of the vehicle is provided with an extension rod 19 similar in construction and arrangement to the 70 other extension rods 14 except that one end of the rod 19 is rotatably mounted within a suitable plate 20 rigidly secured to the said dash board 26. An arm 21 is rigidly secured to that end of the rod 19 rotatably 75 mounted within the plate 20 and is insulated from the said plate 20. A series of stops or contacts 22, 23 and 24, representing charging, releasing and starting positions, respectively, of the valves 6, are secured to 80 the plate 20. The contact 23, representing the starting position, is also insulated from the plate 20. One of the wires 25 of the igniting circuit of the motor is interrupted or severed at any proper place and one of 85 the ends of the said wire is connected to the arm 21 while the other end is connected to the insulated stop 23.

The threaded extension 17 of one rod 14 is screwed into the valve 6 in the adjacent valve casing 3, the annular flanges 12 and 15 thereby providing a means for properly retaining the valve 6 in proper alinement. The valves 6 are in this manner connected together and by means of the rod 19 are 90 also connected to the arm 21 on the dash board 26 so that when the said arm 21 is partially rotated all of the valves 6 will be 95 partially rotated in unison.

The operation is as follows: The arm 21 is turned to the charging position as indicated in Fig. 6 of the drawings which will 100

turn all of the valves 6 to the position indicated in Fig. 2 of the drawings. While the arm 21 is in this position it will be observed, by referring to Fig. 6, that the igniting system will be broken. By turning the engine over several times the piston 27 of each cylinder will draw from the carburetor and compress a quantity of properly mixed explosive gas through the channels 5, 8 and 4 into the chambers 1, the valve 9 permitting the flow in that direction. Inasmuch as the igniting system has been temporarily disconnected by the arm 21, the compression of the gases within the cylinders 2 will not be ignited at the ends of the said compression strokes. As each chamber 1 is charged the charge will be retained therein by the valve 9 which is arranged to prevent a return flow of the gas when the pistons 27 move downward while the other chambers of the series are being charged. After all of the chambers 1 are charged the arm 21 is turned to the contact 23 which restores the connection in the igniting circuit and simultaneously turns all of the valves 6 to the position indicated in Fig. 3 of the drawings, where it will be observed that the interiors of the chambers 1 are disconnected or shut off from the interiors of the cylinders 2 so that the firing of the charges within the cylinders 2, while the motor is running, will not be communicated to the compressed charges within the chambers 1.

In order to start the motor from the compressed charges within the chambers 1, the arm 21 is turned to the contact or stop 24, which will turn all of the valves to the position indicated in Fig. 4 of the drawings. By referring to this figure, it will be observed that the free channels 7 of the valves 6 will provide a direct unobstructed connection between the chambers 1 and the cylinders 2; and the compressed charge of properly mixed explosive gas will then flow from the chambers 1 to the cylinders 2. Inasmuch as one of the pistons 27 will be on the compression or firing stroke, it is obvious that by turning the arm 21 onto the contact 23, the valves will first be turned to the closed position, as indicated in Fig. 3 of the drawings, and the igniting circuit will be completed, which will ignite the charge in one of the cylinders 2 and thereby provide sufficient energy to turn the motor over until the charge in one of the other cylinders is compressed and ignited in the usual manner, and so on until all of the initial charges are ignited and the motor is running normally. In order to recharge all of the chambers 1 ready for the next starting operation, while the motor is running the arm 21 is turned to the stop 22, which will first interrupt and disconnect the igniting circuit and then turn all of the valves 6 to the position indicated in Fig. 2 of the

drawings. The acquired momentum of the motor will be sufficient to cause the pistons 27 therein to draw from the carburetor, in the usual manner, and compress into the chambers 1 a quantity of properly mixed explosive gas, the valves 9 being adapted to prevent the escape of the said compressed charge in the manner hereinbefore described. The chambers 1 will then be ready for the next starting operation, which may be accomplished by first turning the arm 21 to the releasing position or stop 24 and turning the said arm 21 to the starting contact 23 as hereinabove set forth.

It is obvious from the foregoing that I have provided means for storing an auxiliary charge of properly mixed explosive gas arranged to start the motor. I have also provided means for temporarily disconnecting the igniting circuit and simultaneously releasing the compressed charges of explosive gas into the cylinders, as well as means for disconnecting the auxiliary compressed charges from the cylinder while the motor is running, thereby preventing the premature explosion of the said auxiliary charges. I have also provided improved means for igniting the charges after the same have been released into the cylinders of the motor.

The details of construction are so susceptible to variation that I do not wish to confine myself to the precise construction shown herein, but rather to avail myself of any modification that may properly fall within the scope of my invention.

Having thus described my invention what I claim as new and desire to secure by Letters Patent is—

1. A starter for internal combustion motors comprising a series of chambers, each chamber being connected to one of the cylinders and arranged to contain a quantity of properly mixed explosive gas under pressure; a valve interposed between each cylinder and the chamber therefor, said valve having a channel arranged to permit the passage of gas from the cylinder to the chamber and a second channel arranged transversely to the first mentioned channel and having a valve therein arranged to normally permit the passage of gas in one direction only; and means connected to all of the first mentioned valves and adapted to temporarily disconnect the igniting circuit of the motor when either channel of the said valve is in connection with the chamber and cylinder.

2. A starter for internal combustion motors comprising a series of chambers, each chamber being connected to one of the cylinders and arranged to contain a quantity of properly mixed explosive gas under pressure; a valve interposed between each cylinder and the chamber therefor, said valve having a channel arranged to permit the

passage of gas from the cylinder to the chamber and a second channel arranged transversely to the first mentioned channel and having a valve therein arranged to normally permit the passage of gas in one direction only; and means connected to all of the first mentioned valves and adapted to temporarily disconnect the igniting circuit of the motor when either channel of the said 5 valve is in connection with the chamber and cylinder and to connect the said circuit when neither channel is in connection with the said cylinders and chambers.

3. A starter for internal combustion 10 motors comprising a series of chambers, each chamber being connected to one of the cylinders and arranged to contain a quantity of properly mixed explosive gas under pressure; a valve interposed between each cylinder and the chamber therefor, said valve having a channel arranged to permit the 15 passage of gas from the cylinder to the chamber and a second channel arranged transversely to the first mentioned channel 20 and having a valve therein arranged to normally permit the passage of gas in one direction only; a plate rigidly secured to a dash board; a series of stops representing the charging, starting and releasing positions of the valves secured to the plate; a 25 rod operatively connected to all of the first mentioned valves and having one end thereof rotatably mounted within the plate; and a suitable arm rigidly secured to and insulated from the rod and adapted to disconnect the igniting circuit of the motor when either channel of the first mentioned valves are in connection with the chambers and cylinders, to connect the said circuit when neither channel is connected with the said 30 cylinders and chambers and to indicate the position of the said first mentioned valves.

4. A starter for internal combustion 35 motors comprising a series of chambers, each chamber being connected to one of the cylinders and arranged to contain a quantity of properly mixed explosive gas under pressure; a valve interposed between each cylinder and the chamber therefor, said valve having a channel arranged to permit the 40 passage of gas from the cylinder to the chamber and a second channel arranged transversely to the first mentioned channel 45 and having a valve therein arranged to normally permit the passage of gas in one direction only; a plate rigidly secured to a dash board; a series of stops representing the charging, starting and releasing positions of the valves secured to the plate; a 50 rod operatively connected to all of the first mentioned valves and having one end thereof rotatably mounted within the plate; and a suitable arm rigidly secured to and insulated from the rod and adapted to disconnect the igniting circuit of the motor when either channel of the first mentioned valves are in connection with the chambers and cylinders, to connect the said circuit when neither channel is connected with the said 55 cylinders and chambers and to indicate the position of the said first mentioned valves.

In witness whereof I hereunto set my signature in the presence of two subscribing witnesses.
